UNITED STATES PATENT OFFICE.

HENRY WELLS, OF CAMBRIDGE, MASSACHUSETTS.

IMPROVEMENT IN CLOTHES-PINS.

Specification forming part of Letters Patent No. 128,934, dated July 9, 1872.

To all to whom it may concern:

Be it known that I, HENRY WELLS, of Cambridge, in the county of Suffolk and in the State of Massachusetts, have invented certain new and useful Improvements in Clothes-Pins; and do hereby declare that the following is a full, clear, and exact description thereof, reference being had to the accompanying drawing and to the letters of reference marked thereon making a part of this specification.

The object of my invention is to prevent the ordinary crotched clothes-pin from splitting when pressed upon the clothes to secure them to the line; and it consists in a groove and shoulder being formed in the pin at or immediately above the crotch for the insertion of a ring of metal or other suitable material.

In order to enable others skilled in the art to which my invention appertains to make and use the same, I will now proceed to describe its construction and operation, referring to the annexed drawing, in which—

Figure 1 is a perspective view, and Fig. 2 a

longitudinal section, of my improved clothes-pin.

A represents the ordinary wooden crotched clothes-pin. At or immediately above the crotch is made a groove around the pin with a shoulder, *a*, projecting down over the same, and in said groove is placed a ring, *b*, of metal or other suitable material, which will strengthen the pin at the crotch and prevent it from splitting.

Having thus fully described my invention, what I claim as new, and desire to secure by Letters Patent, is—

A clothes-pin, *A*, provided with groove and shoulder *a* and ring *b*, substantially as and for the purposes herein set forth.

In testimony that I claim the foregoing I have hereunto set my hand this 16th day of May, 1872.

HENRY WELLS.
